DESIGN FOR A MACHINE FOR SIGNING FACSIMILE SIGNATURES

Walter L. Todd and Richard C. Browne, Rochester, N. Y., assignors to The Todd Company, Inc., Rochester, N. Y., a corporation of New York

Application April 19, 1938, Serial No. 76,598

Term of patent 14 years

To all whom it may concern:

Be it known that we, Walter L. Todd and Richard C. Browne, both citizens of the United States and residents of Rochester, in the county of Monroe and State of New York, have invented a new, original, and ornamental Design for a Machine for Signing Facsimile Signatures, of which the following is a specification, reference being had to the accompanying drawing, forming a part thereof.

bodying our design, looking at it obliquely from one side, the essential features of the design being shown in full lines.

We claim:

The ornamental design for a machine for signing facsimile signatures, substantially as shown and described.
